UNDERGARMENT

Walter C. Powell, Muskegon, Mich., assignor
to Amazon Knitting Company, Muskegon,
Mich.

Application September 24, 1938, Serial No. 231,463

3 Claims. (Cl. 128—159)

This invention relates to improvements in undergarments.

The main objects of my invention are:

First, to provide a novel men's undergarment 5 of the trunk or "short" type.

Second, to provide an undergarment of the type described having novel provisions for rendering the same smoothly fitting and free from chafing.

10 Third, to provide an undergarment of the type described characterized by a mild supporting effect.

Further objects pertaining to details and economies of my invention will appear from the 15 description to follow. The invention is defined in the claims. A garment which embodies the features of my invention is clearly illustrated in the accompanying drawing, in which:

Fig. 1 is a front view illustrating the under- 20 garment of my invention.

Fig. 2 and Fig. 3 are enlarged fragmentary views in section on lines corresponding to lines 2—2 and 3—3 respectively of Fig. 1.

The present invention relates to a men's under- 25 garment of the trunk or "short" type. Such undergarments have come into extensive use but have heretofore been subject to objections due to the fact that they are uncomfortably tight by reason of their lack of provision to accommo- 30 date the body of the wearer other than by stretching of the material. My invention aims to overcome this difficulty by providing an undergarment which, while form fitting in nature and characterized by a mild supporting action, has 35 further provisions for conforming to the outline of the body of the wearer without unduly stretching the material thereof and resultant binding or chafing of the body of the wearer.

In the drawing the reference numeral 1 indicates the undergarment of my invention which 40 consists of a back portion 2 and integral front and side portions 3, the last named portions terminating at upwardly-converging edges 4 in spaced relation on the front of the garment. 45 These edges are connected by the front or fly portion of the garment, generally indicated 5, which will be hereinafter described, and the seam is finished and reinforced by the tape 6 which is preferably formed of knitted tubing in 50 which the wales run longitudinally or vertically of the garment, the same as the walls of the body fabric.

The rear portion 2 is brought forwardly and upwardly to provide a crotch portion 7 which 55 terminates in a forwardly and downwardly dis-

posed arcuate flap or tongue 8 (see Fig. 3). The outermost edges of the crotch and side and rear portions are secured together and finished by a hem or tape 9, outlining a leg opening 10. A suitable elastic band 11 is enclosed in the hem 9 5 formed by bindings of knitted material to assure yielding though snug engagement with the legs of the wearer.

The front or fly portion 5 of the undergarment is constituted by inner and outer panels 12, 13, 10 which are each stitched to the spaced edges 4 of the side portions 3, with the joint or seam covered by the finish material 6. The panels 12, 13 are provided with arcuate lower ends 14 similar to the arcuate end of tongue 8, and are 15 stitched together and to the said tongue in the manner illustrated in Figs. 1 and 3, with the arcuate ends in registry, thus providing a pouch 16 between tongue 8 and panel 12 which is dis- 20 finit from the crotch portion.

The outermost front panel 13 is left free from the adjacent edge 4 and is cut back at 16 to provide a partially opened fly closure at one side of the front panels. The innermost panel 12 is similarly left free from the opposite edge 4 and 25 cut back to provide a second fly closure staggered laterally of the first. The exposed edges of the panels where they are cut back are hemmed or 30 taped as indicated at 17 to finish the same. It will be noted that the tapes 6 extend to and 35 are connected to the leg bindings and that the seam 19 joining the parts 8 and 14 also extends to the binding joining the same near the lower ends of the tapes. The garment is completed by a suitable continuous web of elastic 18 secured 40 to the upper edge thereof to engage the waist of the wearer.

The material of the undergarment is disposed with the ribs or wales thereof running from top to bottom whereby to render the garment readily 45 stretchable laterally but relatively non-extensible longitudinally, i. e., in the direction of the ribs or wales.

From the foregoing it will be seen that although my undergarment has ample provision 45 for conforming to the body of the wearer and affording adequate support without undue stretching of the material and resultant tight gripping and chafing, the tension set up in the garment in use is just sufficient to maintain the 50 undergarment in snug, smooth, non-chafing relation to the body of the wearer, pouch 15 providing the additional material requisite for this purpose. Furthermore, this tension is sufficient to prevent bulging of the double fly front constituted 55

by panels 12, 13 and the respective openings therein.

The double panel fly front 5 serves to strengthen the resistance of the undergarment to lateral stress, prevents undesired opening of the front, and preserves the smoothness of fit and appearance of the garment. It also contributes materially to the amount of support afforded thereby.

I have illustrated and described my invention 10 in an embodiment which I have found very satisfactory. I have not attempted to illustrate or describe other adaptations which I contemplate as it is believed this disclosure will enable those skilled in the art to embody my improvements 15 as may be desired.

Having thus described my invention, what I claim as new and desire to secure by Letters Patent is:

1. An undergarment for men comprising a body 20 encircling portion having spaced edges at the front of the garment extending up and down the same and a crotch portion terminating in an extended arcuate tongue adjacent the front of the garment, and a double panel front comprising a 25 pair of front panels secured at their sides to said spaced edges and having arcuate ends secured to said tongue with the arcuate portions in register to provide a double walled front pouch adjacent to but distinct from the crotch portion, there being an opening provided between each of said

panels and an adjacent edge of said body encircling portion, said openings being on opposite sides of the double panel front whereby to provide staggered double fly front openings for the garment, said crotch portion and body portion 5 being secured together at the front of the garment to provide leg receiving openings.

2. An undergarment comprising a rear portion and side and crotch portions connected thereto and outlining therewith a pair of leg openings, 10 said side portions terminating in spaced edges on the front of the garment, and a pair of front panels disposed between said edges and stitched to each thereof, said crotch portion having an arcuate tongue extending forwardly and 15 downwardly and the panels having corresponding arcuate ends in registry with and stitched to said tongue.

3. An undergarment comprising a rear portion and side and crotch portions connected thereto 20 and outlining therewith a pair of leg openings, said side portions terminating in spaced edges on the front of the garment, and a front panel disposed between said edges and stitched thereto, 25 said crotch portion having a tongue extending forwardly and downwardly and the panel having an extended end stitched to said tongue to provide a pouch of predetermined size connected to but distinct from said crotch portion.
